UNITED STATES PATENT OFFICE.

GEORGE A. JOHNSON, OF CHICAGO, ILLINOIS, ASSIGNOR TO WILLIAM H. MINER, OF CHAZY, NEW YORK.

RAILWAY-CAR DRAFT-RIGGING.

1,205,997.

Specification of Letters Patent. Patented Nov. 28, 1916.

Application filed November 30, 1914. Serial No. 874,663.

To all whom it may concern:

Be it known that I, GEORGE A. JOHNSON, a citizen of the United States, residing at Chicago, in the county of Cook and State 5 of Illinois, have invented a certain new and useful Improvement in Railway-Car Draft-Riggings, of which the following is a full, clear, concise, and exact description, reference being had to the accompanying drawings, forming a part of this specification.

This invention relates to improvements in railway car draft riggings.

An object of the invention is to provide a draft rigging for railway cars which is in 15 the nature of a combination friction and spring gear and in which an easy draft action is provided.

The invention furthermore consists in the improvements in the parts and devices and 20 in the novel combinations of the parts and devices, as herein shown, described or claimed.

In the drawing forming a part of this specification, Figure 1 is a vertical sectional view of a draft rigging embodying my improvements. Fig. 2 is a horizontal sectional view taken on the line 2—2 of Fig. 1 and showing the gear under full buff. Figs. 3 and 4 are vertical sectional views taken on 30 the lines 3—3 and 4—4 respectively of Fig. 1 and Fig. 5 is a view, similar to Fig. 2, but showing the parts under full draft.

In said drawings, 10—10 denote the center or draft sills each of which is provided 35 with three elongated slots 11, 12 and 13, the slots 11 receiving a movable key 14; the slots 12 a movable key 15; and the slots 13 a movable coupler key 16. Mounted between the sills and on the keys 14 and 15 is an elongated combined friction cylinder and spring 40 casing 17, the friction cylinder portion 18 being at the front and the spring casing portion 19 at the rear. Said friction cylinder and casing is provided with slots 20 at the

45 rear through which passes the key 14 and is prevented from longitudinal movement therein. Said members are also provided with additional elongated slots 21 at the front thereof through which extends the key 50 15, the latter being also longitudinally movable in said slots. The keys 14 and 15 also pass through slotted rear and front followers 22 and 23 respectively which are substantially cylindrical to fit the cylindrical shell

and casing. Mounted between said followers are nested springs 24.

Within the friction shell portion 18 is mounted any suitable friction device and, as shown, the same consists of a plurality of friction shoes 25, wedge 26, anti-friction rollers 27, spring 28, connecting bolt 29 and spring washer 30 thereon. The rear ends of the friction shoes engage the front face of the front follower 23 under normal position of the parts. The coupler 31 is operatively connected to the gear proper by the coupler key 16 and side links 32, each side link 32 being provided with three elongated slots 33 in each of which moves one of the keys 14, 15 or 16.

The operation of the device is as follows:—In normal position of the parts the key 16 is positioned centrally within the slots 13; the key 15 at the front ends of the slots 12; and the key 14 at the rear end of the slots 11. Upon inward movement of the draw bar, the wedge and friction shoes are operated thereby and movement thereof is resisted by the nested springs 24 through the front follower 23, which is moved rearwardly with the key 15. During this movement, the shell 17 is prevented from rearward movement, as is also the rear follower 22, the springs being compressed between the two followers. Under draft, the key 16 pulls the links 32 forwardly and the key 15 being held against the front edges of the slots 12, the front follower 23 is prevented from forward movement. The links 32 however pull the rear key 14 forwardly and thus the shell 17 and the rear follower 22 so that the springs are compressed between the followers. In this action it will be noted no pressure from the springs 24 is exerted against the friction devices, consequently the gear acts as a spring gear only under draft and as a spring friction gear under buff, thus providing an easy draft action yet at the same time providing sufficient capacity under buff.

I claim:—

1. A draft rigging for railway cars comprising in combination, draft sills, a friction shell, friction devices coöperable therewith, a spring, keys extending through said shell and sills and supporting the shell, one of said keys being located intermediate the friction devices and the spring and movable in

only one direction from normal, whereby the friction devices and springs are both actuated under buff and only the spring under draft.

5. 2. In a railway draft rigging, the combination with a longitudinally movable friction shell having friction devices coöperable therewith, of a follower in the rear of said friction devices, means preventing movement of said follower in one direction from normal, a second follower, a spring between said followers, and a draw bar, whereby the friction devices are movable with the shell but inoperative when said first named follower is stationary.
10. 3. In a draft rigging for railway cars, the combination with a draw bar, of a longitudinally movable friction shell having friction devices coöperable therewith, the draw bar engaging the latter under buff, a follower in the rear of the friction devices, a spring in the rear of said follower, a second follower at the rear of said spring, said first follower being movable under buff only and the second named follower under draft only.
15. 4. A draft rigging for railway cars comprising in combination, a draw bar, a friction shell having friction devices coöperable therewith, the draw bar engaging said devices under buff, a pair of followers located in the rear of said friction devices, a spring between said followers, longitudinally movable keys extending through said followers, one of said keys being movable only under buff and the other only under draft, and means connecting said keys with the draw bar.
20. 5. In a railway draft rigging, the combination with a friction shell having

spring case, said shell being provided with 4 slots at the rear and elongated slots near the front thereof, keys extending through said slots, followers on said keys within said shell, a spring between said followers, friction devices located forwardly of the front follower, and links arranged to connect said keys with the draw bar.

6. In a railway draft rigging, the combination with draft sills each provided with a series of elongated slots, of a friction shell having two sets of slots one set of which is elongated, keys extending through said slots and through said slots in the sills, friction devices in front of the key passing through the elongated slots in said shell, 55 springs between said keys and links arranged to connect said keys with a draw bar, the key passing through the rear of said shell being held stationary during buff and said other key being held stationary under 60 draft.

7. In a railway draft rigging, the combination with slotted draft sills, of slotted links, a draw bar, a coupler key connecting said draw bar with the links, a friction shell, 65 friction devices coöperable with said shell, an intermediate and a rear key passing through slots in said shell, slots in said links and slots in said sills, a spring between said intermediate and rear keys, and followers 70 mounted on said intermediate and rear keys, the intermediate key being movable under buff only and the rear key under draft only.

GEORGE A. JOHNSON.
